PIVOT FOR ADJUSTABLE FULCRUM PLIERS

Willard C. Kress, Grand Island, N. Y., assignor to
J. H. Williams & Co., Buffalo, N. Y.

Application February 16, 1948, Serial No. 8,581

4 Claims. (Cl. 81—51.3)

1

This invention relates to adjustable jaw pliers, sometimes also called water pump pliers. In pliers of this type the pivot or fulcrum secured to one of the hinged elements is adjustable at the crossing with the other element along that element, to give the opposed clamping jaws between the elements a desired spacing when the jaws are parallel and the handle ends are also about parallel. Adjustable fulcrums or pivots for this purpose are known, but in handling them the pivotal point of coupling is likely to shift unintentionally, which requires one to stop and reset them, thus causing annoyance and delay in the use of the pliers.

An object of this invention is to provide improved adjustable jaw pliers, which will yieldingly resist any change in any spacing or setting of the clamping jaws, in which the fulcrum or pivot between the hinged elements may be easily, conveniently and quickly shifted along one of those elements to vary the initial spacing between their opposed clamping jaws, and held against unintentional or accidental change from any adjusted relation, which will have maximum strength, and which will be relatively simple, compact, practical, durable and inexpensive.

Other objects and advantages will be apparent from the following description of one embodiment of the invention and the novel features will be particularly pointed out hereinafter in the appended claims.

In the accompanying drawing:

Fig. 1 is a face elevation of a pair of pliers embodying this invention;

Fig. 2 is an edge elevation of the same;

Fig. 3 is a sectional elevation of a part of the same, the section being taken approximately along the line 3—3, Fig. 2, the hinged elements being separated on the pivot to open the jaws into the position in which the normal spacing between the jaws may be changed; and

Fig. 4 is a sectional elevation through the pivotal coupling between the hinged elements, and on a larger scale, to illustrate one form of detent that may be employed.

In the illustrated embodiment of the invention, the pliers have a pair of metal crossing elements 1 and 2 which are pivotally coupled or hinged together by a metal pivot or fulcrum member 3, which conveniently may be a bolt that passes through the elements at their crossings. The member 3 holds the elements 1 and 2 together during their hinged movements. One pair of corresponding ends 4 and 5 of the elements have opposed clamping jaws 6 and 7, and

5 the opposite or other pair of ends are suitably formed to serve as handles 8 and 9, which are generally parallel to each other but spaced somewhat apart when the jaws are parallel to each other, as shown in Fig. 1.

One of these elements, such as element 1 is provided, at the zone of crossing with the other element, with a plurality of slightly intersecting, cylindrical apertures 10 of equal size and extending from face to face of that element and arranged in a row extending in a direction lengthwise of that part of the element in which they are provided. The openings 11 at the intersections between adjacent apertures 10 have diameters considerably less than the diameters of the apertures 10 so as to provide restricted passages connecting adjacent apertures.

The shank of the bolt or pivot member 3, in the portion thereof which passes through any 10 of the apertures 10 was initially cylindrical but has its opposite sides cut off to provide flat, parallel faces 12 and 13 which extend between and connect the convex end bearing surfaces 14, that having a common center of curvature, 15 the resultant shape of this part being an interior segment of a cylinder. The diameter between the convex surfaces 14 is slightly less than the diameter of each of the apertures 10, so as to have a rotary bearing in any aperture 10. The thickness of the segment, which is the distance between faces 12 and 13, is slightly less than the diameter or distance across the intersection openings or passages 11 between apertures 10. The bolt 3 is fixed at its head in element 2 in 20 any suitable manner, so that it will not rotate thereon. It is so fixed that when the handles 8 and 9 are approximately parallel, as shown in Fig. 1, the flat surfaces 12 and 13 will be crosswise of the length of the slot formed by the row of apertures, and convex surfaces 14 of bolt or fulcrum 3 will have rotary bearing in the aperture 10 through which it passes. This prevents movement of member 3 out of the aperture along the slot. When the handles are swung far apart, 25 as shown in Fig. 3, the flat faces 12 and 13 will be parallel with the length of the slot and can pass from aperture to aperture to adjust the pivot or fulcrum and thus space the clamping jaws 4 and 5.

30 A spring pressed ball detent unit 15 is recessed into one of the flat faces, such as face 12 (see Fig. 4) with the ball 16 thereof projecting a little outwardly beyond face 12. A flange 17 at the outer end of the recess restrains ball 16 35 from ejection from the recess 18 by a compressed

spring 19, as usual in ball detents. When the jaws are opened, as shown in Fig. 3, the ball resists movement of member 3 from aperture to aperture by engaging with the restricted passages 11, as shown in Fig. 3. With jaws 4 and 5 opened, as shown in Fig. 3, one may force the member 3 endwise from aperture to aperture, during which the ball 16 is cammed or forced into recess 18 against the action of spring 19 to pass through passages 11. The nut 20 and member 3 keep the elements 1 and 2 coupled together.

It will be observed that one may, by using some force, shift the fulcrum member 3 from aperture to aperture to space the clamping jaws when the jaws are fully opened, yet when the jaws are in normal, working positions, the shifting of the fulcrum member 3 is impossible. The spring detent prevents accidental or unintentional shifting of the member 3. The pivotal coupling between the elements is very simple, compact, strong, and easily manipulated.

It will be understood that various changes in the details, shapes, materials and arrangements of parts, which have been herein described and illustrated in order to explain the nature of the invention, may be made by those skilled in the art within the principle and scope of the invention as explained in the appended claims.

I claim:

1. A pair of adjustable jaw pliers comprising a pair of elements crossing each other intermediate of their ends, one pair of corresponding ends being formed with cooperating, opposed clamping jaws and the other pair of ends being formed as handles, one of said elements having, intermediate of its ends and at the crossing by the other element, a plurality of spaced apart, equal size apertures from face to face, connected by passages of considerably lesser width than the aperture diameters, and arranged in a row extending in a direction lengthwise of that portion of that element in which they are located, the other of said elements having an aperture in the portion that crosses said one element, and a pivot member passing through said last named aperture and one of the apertures in said row and pivotally connecting said elements and holding them against separation, the periphery of that portion of said member which passes through said one element having diametrically opposite convex bearing surfaces with a common center of curvature and separated by diametrically opposite flat surfaces, the distance between said flat surfaces being slightly less than the width of each of said passages, and said convex surfaces having rotary bearing in any aperture of the row through which it passes, and a spring-pressed, ball detent recessed into one of said flat surfaces with its ball projecting from that flat surface a distance from the opposite flat surface greater than the width of each of said passages to normally resist movement of said pivot member through the adjacent passages from aperture to aperture in said row when said flat surfaces are parallel to the length of said row, but yielding under pressure that depresses said ball until the member passes from one aperture to another in said row.

2. A pair of adjustable jaw pliers comprising a pair of elements crossing each other intermediate of their ends, one pair of corresponding ends being formed with cooperating, opposed clamping jaws and the other pair of ends being formed as handles, one of said elements having, intermediate of its ends and at the crossing by

the other element, a plurality of slightly intersecting, equal size, cylindrical apertures arranged in a row extending in a direction lengthwise of that portion of that element in which they are provided, the other of said elements having an aperture in the portion that crosses said one element, a pivot member passing through aligned apertures in said elements at their crossing, pivotally connecting them and confining them from separation, the portion of said member which passes through said one element having the shape of a cylinder segment with diametrically opposite flat faces separated a distance slightly less than the openings at the intersections between adjacent apertures in said row, the opposite cylindrical surfaces of the segment having a rotary bearing in any apertures of the row through which it passes, and a spring-pressed ball detent recessed in one of said flat faces with the ball projecting from that flat face until it yieldingly resists movement of the member through any opening between intersecting apertures when the flat faces are approximately parallel to the length of the row, but yielding under pressure to permit movement of said member from aperture to aperture in the row.

3. A pair of adjustable jaw pliers comprising a pair of elements crossing each other intermediate of their ends, one pair of corresponding ends being formed with cooperating, opposing clamping jaws and the other pair of ends being formed as handles, one of said elements having, intermediate of its ends and at the crossing by the other element, a plurality of slightly intersecting, equal size, cylindrical apertures arranged in a row extending in a direction lengthwise of that portion of that element in which they are provided, the other of said elements having an aperture in the portion that crosses said one element, a pivot member passing through aligned apertures in said elements at their crossing, pivotally connecting them and confining them from separation, the portion of said member which passes through said one element having the shape of a cylinder segment with diametrically opposite flat faces separated a distance slightly less than the openings at the intersections between adjacent apertures in said row, the opposite cylindrical surfaces of the segment having a rotary bearing in any aperture of the row through which it passes, a detent movable into and partially out of said member through one of said flat faces and when partially out increasing the effective thickness from face to face until it is greater than the opening of the intersection between adjacent apertures in the row, and a spring part urging said detent in an outward direction.

4. A pair of adjustable jaw pliers comprising a pair of elements crossing each other intermediate of their ends, one pair of corresponding ends being formed with cooperating, opposed clamping jaws and the other pair of ends being formed as handles, one of said elements having, intermediate of its ends and at the crossing by the other element, a plurality of slightly intersecting, equal size, cylindrical apertures arranged in a row extending in a direction lengthwise of that portion of that element in which they are provided, the other of said elements having an aperture in the portion that crosses said one element, a pivot member passing through aligned apertures in said elements at their crossing, pivotally connecting them and confining them from separation, the portion of

said member which passes through said one element having the shape of a cylinder segment with diametrically opposite flat faces separated a distance slightly less than the openings at the intersections between adjacent apertures in said row, the opposite cylindrical surfaces of the segment having a rotary bearing in any apertures of the row through which it passes, and a yielding projection from one of said flat faces which yieldingly resists passage of said member from aperture to aperture in said row when said flat faces are approximately parallel to the length of said row.
